UNITED STATES PATENT OFFICE.

DANIEL MILLS, OF PHILADELPHIA, PENNSYLVANIA, ASSIGNOR TO
STANDARD SEWING MACHINE COMPANY, OF CLEVELAND, OHIO,
A CORPORATION OF OHIO.

STOP MECHANISM FOR SEWING-MACHINES.

SPECIFICATION forming part of Letters Patent No. 783,701, dated February 28, 1905.

Application filed August 29, 1900. Serial No. 28,395.

To all whom it may concern:

Be it known that I, DANIEL MILLS, a citizen of the United States, and a resident of Philadelphia, in the State of Pennsylvania, have invented certain new and useful Improvements in Stop Mechanism for Sewing-Machines, of which the following is a specification, reference being had to the accompanying drawings, forming part thereof.

- This invention relates to that class of sewing-machines provided with a mechanism for automatically stopping the machine after a certain predetermined number of stitches have been made; and it consists of improvements upon the stop mechanism disclosed in Letters Patent No. 635,267, granted to me October 11, 1899. In said prior patent the buttonhole-sewing machine therein disclosed is provided with a fast pulley on the driving-shaft and a stop mechanism for engaging with said pulley to stop the same, and thereby the machine, at a certain predetermined time, the said stop mechanism being automatically operated and controlled from a member of the work-holder-feeding mechanism through the medium of suitable operative connections. In order to reduce to a minimum the jar or strain upon the machine when the same is brought to a stop by the action of the stop mechanism, a means is also provided for throwing off the power in advance of the action of the latter; so that the momentum of the machine, which is sufficient to complete the determined number of stitches, will be so reduced that the positive stopping of the machine by the stop mechanism may be accomplished without undue jar or strain, it being understood that the throw off of the power is regulated to take place a greater or less number of stitches prior to the completion of the buttonhole, according to the speed of the machine. In the event of any change of adjustment in the feeding movement of the work-holder, however, whereby a greater or less number of stitches are caused to be taken in a given length of buttonhole, it has heretofore been necessary, as in my said prior patent, to make a further and independent adjustment to the power-

throw-off-controlling mechanism in order to have the throw off of the power take place at the same number of stitches prior to the completion of the buttonhole as before, as it will be understood that the speed of the machine being the same the power should be thrown off the same number of stitches (or revolutions of the driving-shaft) prior to the completion of the buttonhole and the action of the stop mechanism independent of the number of stitches made in the buttonhole. For instance, if the work-holder-feeding mechanism is adjusted to provide a certain number of stitches for a certain length of buttonhole the power-throw-off mechanism controlled from one of the moving parts of said feeding mechanism is regulated to throw off the power a certain determined number of stitches prior to the completion of the buttonhole, according to the speed of the machine. Then if it is desired to double the number of stitches for the same length of buttonhole such change is secured by adjusting the feeding mechanism whereby the work-holder and certain of its actuating parts will be caused to move at only one-half the former rate of speed, and consequently the stop and power-throw-off mechanisms being actuated and controlled from said feeding mechanism such reduced speed permits just double the number of stitches to be taken between the time the power is thrown off and the stopping of the machine by the stop mechanism. Therefore it becomes necessary in order that the power may be thrown off prior to the action of the stop mechanism the same number of stitches as before to make another and independent adjustment to the throw-off mechanism.

To make such independent adjustments as above referred to occupies considerable time and also causes more or less trouble and inconvenience, and it has therefore been the principal object of my present invention to provide a simple and effective means whereby the one adjustment of the feeding mechanism of the work-holder to regulate the number of stitches to the buttonhole will automatically adjust the action of the power-throw-off mech-

anism relative to the stop mechanism whereby the power will be thrown off at the same pre-determined number of stitches prior to the action of the stop-mechanism independent of 5 the number of stitches to the buttonhole.

Another object of my invention has been to provide an improved means for regulating the action of the power-throw-off mechanism relative to the stop mechanism whereby the power 10 may be thrown off a greater or less number of stitches prior to the action of the stop mechanism, according to the speed of the machine.

A further object of my invention has been to provide an improved stop mechanism of 15 simple and durable construction for automatically stopping the machine within a partial revolution of the driving-shaft without undue jar or shock.

These objects I secure by means of the new 20 and novel construction and combination of parts, as hereinafter set forth in detail and pointed out in the claims.

Referring to the accompanying drawings, Figure 1 is a front elevation of a buttonhole-sewing machine with certain of the parts removed having my invention applied thereto. Fig. 2 is a plan view of the same with the arm and its supported parts in section just above the bed-plate. Figs. 3 and 4 are sectional views 25 through line xx of Fig. 1 looking in the direction indicated by the arrow, showing the position of certain parts of the stop mechanism when in operative and inoperative position, respectively. Fig. 5 is a perspective 30 view of a portion of the rear end of the machine. Fig. 6 is a detail view of a certain part of the power-throw-off-controlling mechanism. Figs. 7 and 8 are detail views illustrating different positions of certain parts of 35 the stop and power-throw-off-controlling mechanisms. Fig. 9 is a plan view of a portion of the bed-plate with certain of the parts supported thereon, showing the connections between the work-holder and its feeding and 40 adjusting mechanism.

In said drawings, the head or frame of the machine, comprising the bed-plate 1 and over-hanging arm 2, the driving-shaft 3, supported in bearings in said arm and extended at its 45 rear end beyond the latter and having a bearing in a bracket-arm 4, secured to the rear end of the machine, the fly-wheel or pulley 5, made fast on said driving-shaft, so as to rotate therewith, and the driving-pulley 6, loosely 50 mounted on the driving-shaft, so as to rotate thereon and also be capable of having a longitudinal sliding movement whereby it may be moved to and from a position of frictional engagement with the fast pulley, are all substantially the same as disclosed in my said 55 prior patent, No. 635,267.

In accordance with my present invention and as a means for automatically stopping the machine upon the completion of a buttonhole or after a certain predetermined number of stitches 60

have been made I provide a lever 7, which is loosely connected at one end with a sleeve 8 upon the driving-shaft, so as to turn and hinge thereon, and at its opposite end is yieldingly held in a normal position against a stop 70 9 on the frame of the machine by means of a coiled spring 10, which latter connects at one end with said lever and at its opposite end with a fixed pin 11 on the machine-frame. A stop-bar 12 is pivotally connected at one end 75 at 13 with said lever 7 and adjacent to its opposite end is provided with a laterally-projecting pin 14, which is engaged by the upper forked end of a vertically-acting slide-bar 15, which latter is supported to slide in a vertically-arranged groove or guideway 16, formed in the rear end of the machine-frame. The stop-bar 12 is provided with a shoulder 17 at its inner end and is adapted to be operated by the vertically-acting slide-bar 15 to move its 80 said shoulder to and from a position for engaging with a lug or projection 18, located on the hub of the fast pulley 5. In the operation of the machine the slide-bar 15 is held in a lowered position by means as will herein- 85 after be described, so as to hold the shoulder 17 on the stop-bar 12 below the path of the said projection 18 on the fast pulley, as shown in Fig. 4. Upon the completion of the buttonhole, however, and after the driving-pulley 90 has been released from operative engagement with the fast or driving pulley in a manner as will hereinafter be described the slide-bar 15 is then automatically released and moved upward to raise the connected end of 95 the stop-bar 12 and locate its said shoulder 17 in the path of the projection 18 on the fast pulley 5, as shown in Fig. 3, whereby it will engage therewith and stop rotation of the pulley and connected driving-shaft in such direction. In the event of the projection 18 on the fast pulley coming into contact with the stop-bar with any considerable degree of force, as is usually the case, the said stop-bar 100 and its supporting-lever 7 will yield outwardly 105 against the pressure of the spring 10, and so prevent injurious jar or strain to the parts. After the force of the momentum is spent the spring 10 then returns the pulley back to its 110 normal and proper stopping position, which is regulated by the contact of the lever 7 against the stop 9. The slot or opening between the forks at the upper end of the slide-bar 15, into which the pin 14 on the stop-bar 115 extends, is formed in the arc of a circle substantially parallel with the periphery of the pulley-hub on which the projection 18 is located, so that the stop-bar will be guided in a path to retain its engagement with the said projection 18 when forced outwardly under 120 the momentum of the pulley 5, as described.

After the pulley 5 has been stopped in its rotation in one direction by the contact of the projection 18 with the yielding stop-bar 12 the same obviously has a backward or rebound 130

movement, which it is necessary to limit in order that the pulley may be brought to a stop with its connected parts in a desired definite position. I provide for the stopping 5 of the pulley on such backward or rebound movement as follows: A lever 19 is pivotally connected at its lower end at 20 with a bracket-arm 21, attached to the frame of the machine, and adjacent to its upper end is provided with 10 an elongated slot 22, through which a bolt 23 on the frame of the machine extends to guide and limit the movement of the lever at such end. A stop-lever 24 is pivotally connected at 25 with the upper end of said lever 19 and is arranged with one end 26 extending into a 15 position opposite the end of the stop-bar 12 and with a space between the same into which the projection 18 of the fast pulley is adapted to be received and engaged at its opposite sides when the machine is to be stopped, 20 as shown in Fig. 3. A coiled spring 27, connecting at one end with a fixed pin 28 on the machine-frame and at its opposite end with the lever 19, as best shown in Fig. 5, serves 25 to yieldingly hold said lever in a normal position with one of the end walls of the slot 22 in contact with the bolt 23, in which position of the same the stop-lever 24 carried thereby is in its normal position relative to the stop-bar to receive the projection 18 therebetween. 30 In order that the inner end of the stop-lever 24 may be raised and lowered with the coöperating stop-bar 12 when the latter is moved to and from its operative position by the connecting slide-bar 15, it is provided with an 35 extension 29, which projects beneath the adjacent end of the said stop-bar and is yieldingly held in contact therewith by means of a coiled spring 30, which connects at one end 40 with the outer end of the stop-lever 24 and at its opposite end with a pin 31 on the lever 19. By such construction and arrangement of the 45 parts the inner end of the stop-lever 24 will be drawn downward by and with the stop-bar 12 when the latter is lowered to its inoperative 50 position below the path of the projection 18 on the pulley, as shown in Fig. 4, and will be moved upward therewith under the action of the spring 30 to an operative position for engaging with the said projection 18, as shown in Fig. 3.

When the stop-bar 12 and stop-lever 24 have been moved to their operative position, as shown in Fig. 3, the projection 18 on the 55 pulley 5 will during the revolution of the latter strike against the stop-lever 24 and force the same downward and out of its path and then be engaged by the stop-bar 12 in the manner as hereinbefore described. Immediately after the projection 18 has passed over and beyond the end of the stop-lever 24 the latter is again returned to its raised position under the action of the spring 30 to receive 60 the projection 18 thereagainst in its backward or rebound movement and yieldingly limit

the rotation of the pulley in such direction, the stop formed by the lever 24 being yieldingly under the tension of the spring 27 in the same manner and for the same purpose as the first or primary stop 17 under the tension of 70 the spring 10, as hereinbefore described. The opposing stops formed by the adjacent ends of the stop-bar 12 and stop-lever 24 being supported as described thus act to yieldingly stop the machine within a partial revolution 75 of the driving-shaft and without injurious jar or strain to the parts.

When the machine is in operation, the vertically-acting slide-bar 15 is held in its lowered position, with the parts 12 and 24 below the 80 path of the projection 18 on the fast pulley 5, by means of a horizontally - movable slide-latch 32, which is supported to slide on the bed-plate of the machine beneath an overhanging portion of the machine-frame, as clearly shown 85 in Figs. 3 and 4. This latch 32 is provided with a lip or projection 33 at one side thereof, (see Figs. 2, 7, and 8,) which engages with the slide-bar 15, within a notch 34 in one side thereof, to hold the same in its said lowered 90 position, and when the machine is to be stopped the latch is withdrawn from its engagement with the slide-bar 15 and the latter is automatically raised under the action of a spring 35, which latter connects at one end 95 with the stationary pin 28 and at its opposite end with a pin 36 on the said slide-bar 15.

The slide-latch 32 might be operated to control the action of the stop mechanism in the manner described by any suitable means; but 100 the same, according to my present invention, is automatically controlled from a rotating driving-gear 37, forming part of the work-holder-feeding mechanism, through the medium of a lever 38, which latter is pivotally 105 supported in a horizontal position upon the bed-plate of the machine at 39, with one end provided with a double-headed bolt 40, engaging with an upturned end 41 of the latch 32, and its opposite end provided with two 110 arms 42 42', which are adapted to be engaged by a pin 43, located on the under side of the disk 37, to communicate a vibrating movement to the said lever 38 in a manner as will be described. 115

In the operation of the machine and when the buttonhole or other work is nearing completion the pin 43 on the rotating gear-disk 37 moves into engagement with the arm 42 of the lever 38 and operates the latter so as to move the connecting slide-latch 32 from holding engagement with the vertically - acting slide-bar 15, as shown in Figs. 2 and 8, and thereby permit the latter to be raised to effect the stopping of the machine. Then in 120 order to again start the machine the said slide-bar 15 is lowered by a suitable connection and held in such lowered position by an engaging spring-pressed latch 44, carried by the slide-latch 32, as shown in Fig. 7, which 130

latch normally presses against the side of the slide-bar 15, so as to automatically snap into a notch 34' therein when the latter is lowered into a position opposite the same. The machine now being set in motion, the pin 43 on the gear-disk 37 is carried by the latter from the position shown in Fig. 8 into a position to engage with the opposite arm 42' of the lever 38 and operate the latter to move the slide-latch 32 into position to again engage with the vertically-acting slide-bar 15 and withdraw the spring-pressed latch 44 from its engagement therewith, as shown in Fig. 7. The running of the machine then continues until the pin 43 again reaches a position to engage with the first arm 42 of the lever 38 and operate the latter to effect the stopping of the machine, as before described.

I will now proceed to describe the mechanism by which the loose driving-pulley 6 may be automatically released from operative engagement with the fast pulley 5 any desired predetermined number of stitches or revolutions of the driving-shaft prior to the stopping of the machine by the action of the stop mechanism. In doing this it will be necessary to first refer to the work-holder and its feeding mechanism, which latter, as herein shown, is substantially the same as that disclosed in detail in my pending applications, bearing Serial Nos. 611,485 and 611,486. This feeding mechanism comprises in part the said main driving-gear 37, which is made fast upon a sleeve 37', which is loosely supported to revolve about a stationary vertical stud 37", located upon the bed-plate of the machine. This driving-gear 37 meshes with a second gear or pinion 45, which latter is also loosely mounted to rotate upon a stud 46 on the bed-plate of the machine and is connected with a ratchet-disk 47, also mounted upon said stud so as to rotate therewith. A lever 48, pivotally mounted upon the stud 46 and carrying a pawl 49 for engaging with the ratchet 47, is provided with a pin 50, connected therewith, which projects below its under side into the groove 51 of a lever 52, which latter is pivoted at one end upon a stud 53 on the bed-plate 1 and at its opposite end provided with a roll 54, carried on its under side, which is engaged through an opening in the bed-plate by a grooved cam 55 on the lower driving-shaft 56. By this arrangement of parts it will be understood that as the lever 52 is vibrated by the cam 55 the lever 48 will also be vibrated thereby and cause the pawl 49 to engage with the ratchet 47 and give the same a rotating step-by-step movement, which is communicated to the driving-gear disk 37 and connected to sleeve 37'.

The work-holder, as herein shown, consists of a lower base-plate 57 and an upper spring-pressed clamping-plate 57', between which the goods containing the buttonhole (indicated at 57") is adapted to be held and clamped. The

means for communicating a longitudinal movement to this work-holder in a direction lengthwise of the buttonhole comprises a cam 58, (shown by dotted lines in Fig. 9,) which is secured upon the said sleeve 37' to be rotated thereby and engages with two antifriction-rolls 59' 59', carried by a yoke-bar 58' to give the latter a longitudinal forward-and-backward movement, which is communicated to the work-holder through the medium of two connecting-levers 60 and 61. These levers 60 and 61 are pivotally supported upon the bed-plate of the machine with their inner or adjacent ends pivotally connected with each other through the medium of a pivot-stud 62 and with their outer ends connecting with the yoke-bar and work-holder at 60' and 61', respectively.

The mechanism for giving the work-holder its lateral or vibratory movement consists of a vibrating elbow-lever 63, which is pivotally supported at 63' upon the bed-plate of the machine, with one arm, 64, thereof having connection with the work-holder-supporting plate 65 through the medium of a pitman 66 and its other arm being provided with two pivoted spring-controlled arms 67 67, which serve as an adjustable medium of connection between the lever 63 and its actuating-lever 68, which latter (only one end of which is herein shown) is adapted to be supported upon the arm of the machine and be operated from the upper driving-shaft in a manner as shown and set forth in detail in my prior application bearing Serial No. 611,485.

The particular construction of the work-holder and its feeding mechanism other than the driving-gear disk 37 and the means for rotating the same do not form a part of my present invention, and therefore may be of any suitable or known construction, the same, as herein shown, being substantially the same as that disclosed in detail in my said prior applications bearing Serial Nos. 611,485 and 611,486.

It will be understood that according to the speed at which the driving-gear 37 rotates the longitudinal movement of the work-holder will be regulated accordingly, and so determine the space between the stitches, and thereby the number of stitches to the buttonhole. Therefore as a means to regulate the number of stitches to the buttonhole the pin 50 is adjustable in a longitudinal slot 48' in the lever 48, whereby it may be moved a greater or less distance from the pivot of the lever 52, and so vary the length of vibration of the lever 48, which being greater or less will vary the distance of each step-by-step movement of the ratchet 47 and the gear 37, driven therefrom, as will be readily understood.

To now describe the means for releasing the driving-pulley 6 from operative engagement with the fast pulley 5, a collar 70 is loosely mounted on the driving-shaft 3 to have

a slight longitudinal movement thereon between the pulley 6 and the bracket-arm 4 and is connected by a pin 71 with a short rod 72, which is loosely supported to slide within the 5 hollow end of the shaft 3, with one end projecting beyond the end of the latter, as clearly shown in Fig. 1. An elbow-lever 73, pivotally supported at 74 upon the bracket-arm 4, is arranged with one arm, 75, extending into a 10 position to engage with the end of the said rod 72 for the purpose of forcing the loose driving-pulley 6 into operative engagement with the fast pulley 5 and its other arm, 76, connecting with a vertically-acting slide-bar 15 15 77 by extending into an opening 77' therein. This slide-bar 77, which I term the "power-slide," is supported to operate in a position adjacent to and parallel with the stop mechanism slide-bar 15 and is provided with two 20 elongated openings 77" 77", through which the pins 28 and 36 extend. Adjacent to its lower end this power-slide 77 is provided with two notches 78 and 78', formed in its opposite edges and in position coinciding with the 25 notches 34 and 34' in the slide-bar 15. A horizontally-acting slide-latch 79, which I term the "power" slide-latch, is supported to operate within a guideway 79' in the machine-frame, as more clearly shown in Fig. 2, and 30 is provided with a shoulder 80, which is adapted when the machine is in operation to engage with the power-slide 77 within the notch 78 therein and hold the same in a lowered position, with the elbow-lever 73 holding the 35 driving-pulley 6 in operative engagement with the fast pulley 5. By withdrawing the power slide-latch 79 from engagement with the power-slide 77 the latter will be automatically raised under the action of a spring 81, and 40 thereby rock the elbow-lever 73 in a direction to release the driving-pulley from its operative engagement with the fast pulley. The said spring 81 for raising the power-slide is connected at one end with a pin 82 on the latter and at its opposite end with a pin 83 on the machine-frame, as clearly shown in Fig. 1.

As a means for automatically operating the power slide-latch 79 I have provided a lever 84, which is pivotally mounted upon a movable stud 85 on the upper surface of the bed-plate, with one end having a pin 86 on its under side extending into a cam-groove 87 in the upper surface of the gear-disk 37 and its opposite end having a pivoted lever 88 secured thereon, which is provided with a forked end 89, engaging with a pivoted block 90 on the outer end of the power slide-latch 79. The said groove 87 in the gear-disk 37 is formed with a part thereof extending in a circular path described from the axis of the disk and at one point therein is provided with the cam portion 91, projecting inwardly from the outer wall of the groove, as clearly shown in Figs. 2, 7, and 8.

65 In the operation of the machine and during

the sewing of a buttonhole the lever 84 is held in a stationary position, with the pin 86 at one end thereof extending into the circular portion of the groove 87 in the disk 37, and the lever 88 at its opposite end holding the power 70 slide-latch 79 in engagement with the lowered power slide-bar 77, as shown in Fig. 7. At this same time the stop-mechanism slide-bar 15 is of course held in its lowered position by the latch 32, also as shown in Fig. 7. Now when 75 the buttonhole is nearing completion and at a certain predetermined number of stitches prior thereto the cam-surface 91 of the groove 87 moves into engagement with the pin 86 on the lever 84 and rocks the latter on its pivot, 80 so as to withdraw the connected latch 79 from engagement with the slide-bar 77, as shown in Figs. 2 and 8 and by dotted lines in Fig. 7, and so permit the latter to effect the release of the driving-pulley from engagement with the 85 fast pulley, and thereby throw off the power. The parts are so adjusted that such throw-off of the power takes place before the pin 43 on the under side of the gear-disk 37 acts upon the stop-mechanism lever 38, and 90 as the machine continues its operation under momentum the said pin 43 is carried by the continued rotation of the gear-disk 37 into engagement with the arm 42 of the lever 38 and rocks the latter on its pivot, so as to 95 move the latch 32 from engagement with the slide-bar 15, as shown in Figs. 2 and 8, and so permit the latter to effect the stopping of the machine as hereinbefore described.

It will be understood that the position of the 100 pin 43 on the gear-disk 37 relative to the arm 42 of the lever 38 at the time the driving-pulley is released from engagement with the fast pulley determines the number of stitches that will be made between the throw-off of the 105 power and the stopping of the machine, as the distance being greater or less in which the pin travels before acting upon the lever 38 sufficiently to effect the stopping of the machine allows a greater or less number of 110 stitches to be made accordingly. Therefore it will be obvious that by adjusting the position of the lever 84 in a longitudinal direction, as indicated by dotted lines in Fig. 8, the cam 91 will be caused to act sooner or 115 later upon the pin 86 of said lever 84, and so permit the pin 43 on the gear-disk 37 to reach a position more or less close to its position relative to the lever 38 for effecting the stopping of the machine. In this manner the 120 throwing off of the power at any desired number of stitches or revolutions of the driving-shaft prior to the stopping of the machine may be regulated.

As before referred to, the throw-off of the 125 power relative to the stopping of the machine is regulated according to the speed at which the latter is running, and consequently, the speed being the same, the power should be thrown off the same number of stitches prior 130

to the stopping of the machine regardless of the number of stitches made in the buttonhole. I provide for this as follows: The lever 84 is provided with an adjustable stop 93 on its upper side, which is adapted to be in a position when the several mechanisms are properly adjusted at one end of the vibrating throw of a pin 92 on the under side of the front end of the feed-mechanism lever 48. We will now 5 consider, for example, that the work-holder-feeding mechanism is adjusted to provide fifty stitches in a buttonhole. If it is then desired to put only one-half the number, or twenty-five stitches, in the buttonhole, the pivot-pin 10 50 is properly adjusted so as to secure a greater throw of the lever 48 and cause the gear-disk 37, driven therefrom, to move double the distance at each of its successive step-by-step 15 movements and communicate such movement 20 to the work-holder. Without further adjustment to the lever 84 the stop mechanism would now be actuated to stop the machine after the throw-off of the power at only one-half the 25 number of stitches as before, on account of the increased distance of the step-by-step 30 movements of the disk 37 in carrying the pin 43 into engagement with the lever 38; but in accordance with my invention when the feeding mechanism is adjusted as described and 35 the machine set in motion the increased throw 40 of the lever 48 causes its pin 92 to engage with the stop 93 on the lever 84 and move the latter longitudinally a distance equal to the increased throw of said lever 48, which change 45 in position of the lever 84 so adjusts the position of its pin 86 as to cause the same to be engaged by the cam 91 on the disk 37 so much sooner than before as to enable the pin 43 to take the same number of step-by-step 50 movements between the throw-off of the power and the stopping of the machine. The timing in the relative actions of the power and stop mechanisms for different numbers of stitches with the machine running at the same speed 55 is thus automatically regulated.

In the event of the speed of the machine being changed it becomes desirable to throw off the power a greater or less number of 50 stitches prior to the action of the stop mechanism, according as to whether the speed is greater or less. To provide for this the stop 93 is adjustable on the lever 84, whereby the latter may be moved a greater or less distance in a longitudinal direction, so as to adjust the 55 position of the pin 86 to effect the throw-off of the power at the desired number of stitches prior to the action of the stop mechanism. The stop 93 is secured in adjustable position on the lever 84 by means of two set-screws 60 94, which engage with the stop-plate through two elongated slots 95, 95 therein, as shown.

As a convenient means for permitting of the sliding adjustment of the lever 84 and

holding it stationary in adjusted position I have mounted its pivot 85 upon a plate 96, which is supported to slide within a groove 97 in the bed-plate of the machine, as shown in Fig. 6. This plate 96 is provided with a pin 98 on its under side, which extends through 70 an elongated slot 99 in the bed-plate and is provided with a flanged head 100. A coiled spring 101 is located on said pin 98, with one end bearing against the head 100 and its opposite end against a plate or washer 102, 75 which latter is loosely supported on the pin 98 and spans the slot 99 in the bed-plate on the under side of the latter. The spring 101 as thus arranged holds the plate 96 in frictional engagement with the bed-plate and 80 serves to hold it stationary in any adjusted position.

The forked lever 88, carried by the lever 84, is pivotally connected at one end at 103 to the latter and is provided with an elongated 85 transversely-arranged slot 104 between its ends, through which a pin 105 on the lever 84 extends to limit the movement of the same. A spring 106 (indicated by dotted lines in Fig. 2) is secured on the under side of the lever 90 84, with one end pressing against a pin 107 on the lever 88 to movably hold the latter in a normal position with one end wall of the slot 104 in contact with the pin 105. The purpose of this construction is as follows: When 95 the slide-bars 15 and 77 have been lowered and the machine set in operation and during such operation the lever 84 is actuated by the cam of the gear-disk 37 to move the latch 79 into position to enter the notch 78 of the slide-bar 77, then in the event of said notch not being in position for any reason to receive the latch the lever 88 will yield under the pressure of the spring 106, so as to prevent 100 breakage or strain to any of the parts and at 105 the same time hold said latch in position, whereby it will be caused to snap into the notch 78 when brought into position opposite the same.

Having thus illustrated and described a 110 practical embodiment of my invention, I do not wish to be understood as confining myself to the particular details of construction and combination of parts as set forth, as the same may be more or less materially modified 115 without departing from the spirit of my invention. Also it will be obvious that the stop mechanism proper may be employed in connection with various kinds of sewing-machines other than a buttonhole-machine as herein 120 shown.

What I claim, and desire to secure by Letters Patent of the United States, is—

1. In a sewing-machine, the combination, 125 with a feeding mechanism and adjusting means therefor, of a stop mechanism, a power-throw-off mechanism, and means for regulating the action of the power-throw-off mechanism rel-

atively to the stop mechanism by the adjustment of the feeding mechanism, for the purpose set forth.

2. In a sewing-machine, the combination, 5 with a feeding mechanism and adjusting means therefor, of a stop mechanism, a power-throw-off mechanism, means for controlling the action of said stop and power-throw-off mechanisms from the feeding mechanism, and means for regulating the action of the power-throw-off mechanism relatively to the stop mechanism by the adjustment of the feeding mechanism, for the purpose set forth.

3. In a sewing-machine, the combination, 15 with a feeding mechanism and adjusting means therefor, of a stop mechanism, a power-throw-off mechanism, means for controlling the action of said stop and power-throw-off mechanisms, and means for regulating the action 20 of the power-throw-off mechanism relatively to the stop mechanism by the adjustment of the feeding mechanism, for the purpose set forth.

4. In a buttonhole-sewing machine, the combination, 25 with the work-holder and its feeding mechanism, of a stop mechanism, a power-throw-off mechanism, means for automatically controlling the action of said stop and power-throw-off mechanisms, and means for regulating the action of the power-throw-off mechanism relatively to the stop mechanism by the adjustment of the work-holder-feeding mechanism, for the purpose set forth.

5. In a buttonhole-sewing machine, the combination, 35 with the work-holder and its feeding mechanism, of a stop mechanism, a power-throw-off mechanism, means forming an operative connection between one of the movable parts of the work-holder-feeding mechanism and the said stop and power-throw-off mechanisms, and means for automatically regulating the action of the power-throw-off mechanism relatively to the stop mechanism by the adjustment of the work-holder-feeding mechanism, for the purpose set forth.

6. In a buttonhole-sewing machine, the combination, 50 with the main driving-shaft having a fast pulley thereon, a loose driving-pulley for engaging with said fast pulley, and the work-holder and its feeding and adjusting mechanism, of a stop mechanism, a power-throw-off mechanism controlling the action of said loose driving-pulley, means for actuating said stop and power-throw-off mechanisms 55 from the work-holder-feeding mechanism, and means for regulating the action of the power-throw-off mechanism relatively to the stop mechanism by the adjustment of the work-holder-feeding mechanism, for the purpose set forth.

7. In a sewing-machine, the combination, 60 with a feeding mechanism embodying a lever, of a stop mechanism, a power-throw-off mechanism embodying an adjustable lever, means 65 for actuating said stop and power-throw-off

mechanisms from the feeding mechanism, and means for adjusting the throw of the said feeding-mechanism lever and thereby regulating the position of the said throw-off mechanism lever, for the purpose set forth.

8. In a sewing-machine, the combination, 70 with a feeding mechanism, of a stop mechanism, a power-throw-off mechanism embodying an adjustable sliding lever, and means for automatically controlling the action of said stop 75 and power-throw-off mechanisms from the feeding mechanism, for the purpose set forth.

9. In a sewing-machine, the combination, 80 with a feeding mechanism, of a stop mechanism, a power-throw-off mechanism embodying an adjustable lever, and means for automatically controlling the action of said stop and power-throw-off mechanisms from the feeding mechanism, for the purpose set forth.

10. In a sewing-machine, the combination, 85 with a feeding mechanism embodying a cam, a power-throw-off mechanism, and means, embodying an adjustable lever, for actuating the power-throw-off mechanism from said cam.

11. In a sewing-machine, the combination, 90 of a feeding mechanism embodying a rotatable cam, and a power-throw-off mechanism, the latter embodying a pivoted lever having a part thereof extending into a position to be engaged by the said cam, the pivot-support of 95 said lever being adjustable whereby the lever may be adjusted in its relation to the said cam, for the purpose set forth.

12. In a sewing-machine, the combination, 100 of a feeding mechanism embodying a vibrating lever and a rotatable cam, and a power-throw-off mechanism embodying an adjustable pivoted lever, the latter being arranged to be operated by the said cam and having an adjustable stop thereon adapted to be engaged by 105 said vibrating lever or a part thereof, for the purpose set forth.

13. In a sewing-machine, the combination, 110 of a power-throw-off mechanism embodying a lever, a stop mechanism embodying a lever, and a feeding mechanism embodying means for successively engaging the said levers to actuate the throw-off and stop mechanisms at certain predetermined times, for the purpose set forth.

14. In a sewing-machine, the combination, 120 of a power-throw-off mechanism and a stop mechanism, each embodying a vertically-acting slide, a spring for moving said slide in one direction, and a latch device for engaging 125 with the slide to hold it against the pressure of the spring in the opposite direction, and a feeding mechanism having means for successively operating said latch devices at predetermined times to effect the operation of first 125 one mechanism and then the other, for the purpose set forth.

15. In a sewing-machine, the combination, 130 of a power-throw-off mechanism and a stop mechanism each embodying a vertically-act-

- ing slide arranged adjacent to each other, a spring for holding said slides in a normal raised position, two independent slide-latches for engaging with said vertical slides and holding the same in a lowered position against the pressure of the spring, a feeding mechanism having means for automatically operating said slide-latches to move the same to and from their position in holding engagement with the vertical slides, and a spring-pressed catch carried by one of the slide-latches for engaging with the vertical slides when first lowered and preliminary to the engagement therewith of the slide-latches, for the purpose set forth.
- 15 16. In a sewing-machine, the combination, of a power-throw-off mechanism and a stop mechanism each embodying a vertically-acting slide arranged adjacent to each other, a spring for holding said slides in a normal raised position, two independent slide-latches for engaging with said vertical slides and holding the same in a lowered position against the

pressure of the spring, a feeding mechanism having means, embodying a yielding part, for automatically operating said slide-latches to 25 move the same to and from their position in holding engagement with the vertical slides, and a spring-pressed catch carried by one of the slide-latches for engaging with the vertical slides when first lowered and preliminary 30 to the engagement therewith of the slide-latches, for the purpose set forth.

17. In a sewing-machine, the combination, with a feeding mechanism, of stop and power-throw-off mechanisms actuated from said feeding mechanism, and means for regulating the action of the power-throw-off mechanism relatively to the stop mechanism, for the purpose set forth.
